UNITED STATES PATENT OFFICE.

CHARLES F. GAUNT, OF BIRMINGHAM, ENGLAND.

COMBINED MEDAL RIBBON-BAR AND MEDAL-SUSPENDER.

1,377,676.

Specification of Letters Patent.

Patented May 10, 1921.

Application filed February 17, 1920. Serial No. 359,333.

To all whom it may concern:

Be it known that I, CHARLES FREDERICK GAUNT, a subject of the King of Great Britain, of Warstone Parade Works, in the 5 city of Birmingham, county of Warwick, England, have invented certain new and useful Improvements in Combined Medal Ribbon-Bars and Medal-Suspenders; and I do hereby declare that the following is a 10 full, clear, and exact description thereof.

This invention has reference to combined medal ribbon bars and medal suspenders. Heretofore these medal ribbon bars and 15 medal suspenders have usually been made in two or more pieces, namely, a top bar and a bottom bar with the double rim sewn at the back and connecting the two bars together, the bottom bar being adapted for the suspension of the medal.

According to my invention I make the 20 combined medal ribbon bar and suspender in one piece with the exception of the actual attachment pin and the suspension pin, and in such a way that the ribbon is attached to the top and to the bottom without sewing. Moreover the medal ribbon is 25 with my invention single instead of being double and thus about one half of the length of the medal ribbon is saved, and the ribbon 30 always remains stretched out to its proper shape so that it has a neat appearance and cannot be pulled out of shape, and moreover the article complete with the ribbon is 35 much cheaper to produce than is the usual combined medal ribbon bars and suspenders.

My invention is illustrated by the accompanying drawings of which—

Figure 1 is a front view of a combined 40 medal ribbon bar and medal suspender constructed in accordance with this invention;

Fig. 2 is a back view of the same;

Fig. 3 is a plan of the sheet metal blank 45 for forming the plate or frame part of the combined medal ribbon bar and medal suspender shown in Figs. 1, 2 and 3, and

Fig. 4 is a sectional side elevation of the same.

In carrying my invention into practice, I 50 provide a plate or frame A, preferably made of sheet metal the width of which from side to side corresponds with the width of the required medal bar from one vertical side to the other, and this plate A is made of convenient depth to suit the proper length 55 of the ribbon B. the lower edge of the plate being preferably chamfered off to the sides

as shown. The said bottom edge may if desired be straight and parallel with the top edge. At the center of the bottom edge there is formed an eye or loop or a pierced 60 ear 1 or the like to receive the vertical swivel pin C at the bottom of which the medal D is suspended. Instead of the center of the bottom part of the plate A being formed with the pierced ear 1, it may be shaped 65 in any other suitable manner for the attachment of the medal. For the attachment of the combined medal ribbon bar and medal suspender to a garment, the upper part of the plate or frame A is provided with any 70 suitable attachment device, preferably a brooch pin E which is jointed at 2 to a loop or the like 3 at one side of the plate A near the top of the same, said pin E being adapted to engage with the hook 4 or the 75 like which is formed at the other side of the plate or frame A. The plate or frame A is preferably of skeleton formation as shown. The upper end of the ribbon B is attached to the top of the bar or plate A 80 by the edge portions 5, 6, of the plate A, being folded over on the top edge of the ribbon B so as to secure the same between the folded edge parts 5, 6 and the back of the plate A. The ribbon B is then folded 85 over the top of the bar or plate A and stretched over the front of the same and the lower end portion of the ribbon is folded over the bottom edges 7 (or edge) 90 on to the back of the same, and these ends are secured by the central tongue part 8 of the frame which is raised and bent and closed over onto the folded end portions of the ribbon B as shown in Fig. 2, thereby 95 effectually securing the ribbon stretched on to the plate or frame.

Or as an alternative arrangement, instead of the top of the ribbon being secured to the top part of the frame by the parts such as 5, 6 being closed over on to the ribbon 100 at the back of the plate or frame as in Figs. 2 and 3, the top edge of the ribbon can be secured to the top of the plate or frame by the top edge parts such as 5, 6 of the latter being turned and closed over at the front 105 on to the top of the ribbon, and in this case these turned over parts 5, 6, may be shaped or stamped with any suitable fancy design. The back plate A is preferably of skeleton formation as shown, but if desired it can be 110 a solid plate as will readily be understood.

The swivel pin C by which the medal D

is suspended is preferably of the usual kind having a head 9 which bears on the top of the central upper eye or ear 10 of the plate or the frame A, the lower portion of the 5 pin C passing as aforesaid through the lower pierced ear 1 and at its lower end being hooked or bent into a loop or eye 11 to engage with the hole or attachment suspension ring of the medal D.

10 Having now particularly described and ascertained the nature of my said invention and in what manner the same is to be performed, I declare that what I claim is:

15 1. A combined medal ribbon bar and medal suspender consisting of a plate adapted to have a ribbon stretched thereon, said plate having portions bent back upon the plate to retain the adjacent ends of the ribbon thereon, projections upon the back of 20 said plate in vertical alinement, a vertically disposed pin mounted in said projections and adapted to support a medal at its lower end and means upon said plate for attachment to a garment.

25 2. A combined medal ribbon bar and medal suspender including a plate adapted to have a ribbon stretched thereon, said plate carrying at the top a hinged brooch pin adapted to secure the combined medal bar 30 and medal suspender to a garment, said brooch pin being secured to the plate or frame by a tongue of the latter passing through an eye of the pin, the opposite side of the plate or frame being made with a 35 hooked projection with which the pin can be engaged.

3. A combined medal ribbon bar and medal suspender including a plate adapted to have a ribbon stretched thereon, said 40 plate having a top backwardly projecting eye and a bottom backwardly projecting eye through both of which passes a headed central vertical suspension pin adapted at its lower end for attachment to a medal.

45 4. A combined medal ribbon bar and medal suspender consisting of a sheet-metal plate adapted to have a ribbon stretched over the front thereof, the top side of said

plate having spaced portions bent back upon the plate to retain the adjacent end of the 50 ribbon thereon and a rearward projection intermediate said bent-back portions and having an eye therein, said plate near its lower end having a punched-out portion bent back to retain the adjacent portion of the ribbon 55 thereon, a second rearward projection at the lower end of said plate and having an eye therein, means adapted to suspend a medal from said plate consisting of a pin extending through said eyes and having an 60 enlarged upper end and a hooked lower end, and means upon said plate for attachment to a garment.

5. A combined medal ribbon bar and medal suspender consisting of a unitary 65 sheet metal plate adapted to have a ribbon stretched over the front thereof, the top side of said plate having spaced portions bent back upon the plate to retain the adjacent end of the ribbon thereon and a rearward 70 projection intermediate said portions and having an eye therein, the lower side of said plate being tapered to a point in vertical alinement with said projection, a second rearward projection upon said point and 75 having an eye therein, said plate having a punched out portion near its lower end and adapted to retain the adjacent portions of the ribbon thereon, means adapted to suspend a medal from said plate consisting of 80 a pin extending through said eyes and having an enlarged upper end and a hooked lower end, and means upon said plate for attachment to a garment, said last-mentioned means consisting of a loop on one side of 85 said plate, a hooked projection on the opposite side thereof and a brooch pin hinged in said loop and adapted to engage said hooked projection.

In testimony whereof I have signed my 90 name to this specification in the presence of two witnesses.

CHARLES F. GAUNT.
